SAMUEL LEATHER, OF DALTON, ENGLAND.

Letters Patent No. 77,498, dated May 5, 1868.

IMPROVEMENT IN LOOM FOR WEAVING GARMENTS.

The Schedule referred to in these Letters Patent and making part of the same.

TO ALL WHOM IT MAY CONCERN:

Be it known that I, SAMUEL LEATHER, of Dalton, in the county of York, England, have invented a new and useful Improvement in Weaving Garments; and I do hereby declare that the following is a full, clear, and exact description thereof, which will enable others skilled in the art to make and use the same, reference being had to the accompanying drawings, forming part of this specification, in which—

Figure 1, sheet 1, is a vertical longitudinal section of a skeleton loom, taken in the line x x , fig. 2, showing the cam-attachment for working the stitching-leaves of the heddles to make the seams of garments.

Figure 2, sheet 1, a top view of the same.

Figure 3, sheet 2, a rear end view, partly in section.

Figure 4, sheet 2, a detached view of one leaf of the heddles.

Figure 5, sheet 2, a modification of the pattern-cam for stitching seams in garments.

Figure 6, an end view of the same.

Figures 7 and 8 are plans of seams in making garments.

Figure 9, sheet 1, plan of seams for stitching double webs of cloth together to make under-shirts.

Figure 10, sheet 1, plan of seams for stitching double webs of cloth together to make pantaloons.

Similar letters of reference indicate like parts.

This invention relates to an improvement in weaving garments or wearing-apparel, such as shirts, pantaloons, drawers, &c., &c., by stitching double cloth together, with seams between the articles, in such manner that a series of the same garments is woven and stitched at the same time, to be afterwards cut apart between the seams, thus effecting great economy in the making of such garments, and a great saving of material, now wasted by cutting the garments out of single cloth after a pattern, to be afterwards sewed together in the usual way.

This object is accomplished by means of a cam or cams attached to a loom for weaving double cloth in such manner that the seams of a series of garments shall be made by stitching the double web together, according to the pattern of the cam, which operates on the stitching-leaf or leaves of the heddles when the fabric is woven, as hereinafter more particularly described.

A represents the skeleton frame of a loom having a jacquard-machine, B, attached, C the warp-beam, D the clc. beam, E the harness, and F the treadles, all constructed and arranged in the ordinary manner for weaving double cloth, the upper web being shown in red, and the lower web in blue, the colors being merely for distinction in describing the operation of stitching the two webs together to form them into garments, as hereinafter described.

Attached to the side of the loom is a shaft, a, carrying a worm-wheel, G, that engages the gear G' on a cam-shaft, b, that runs across the rear end of the jacquard-frame, and carries the stitching-cam or cams H, formed in any desired pattern, for making the seams of the garments to be woven and stitched together in a series, as represented in figs. 9 and 10.

The stitching-cams H may be made narrow-faced, and placed loosely on the cam-shaft b, secured with a feather and groove, to prevent turning thereon, while they travel from end to end of it by means of a series of guide-rods, e e, placed upright on the rear of the jacquard-frame, between which rods the cams revolve and act like a screw, to give them the forward movement on the shaft b that may be required for making a seam.

Or, instead of narrow-faced travelling-cams, H, a single long cam may be employed, having its face formed to give the requisite lifting-movement to the stitching-threads, according to the shape or pattern of the seam to be stitched, one of which single cams is shown in figs. 5, 6.

The action of the stitching-cam is similar to that of a pattern-card cylinder of the jacquard-machine for working the rows of horizontal needles d d, provided, as usual, with spiral springs e e, which needles, when moved back by the cam H, carry one or more of the vertical hooks g g into position for being caught by one or both of the lifter-bars h h of the griff-frame K, which is connected in any suitable way with one of the treadles

F', to lift it for stitching the seam by lifting the hooks *g g*, with the threads of the warp-yarn of the lower web of cloth in heddles *k k*, as presently described.

The perpendicular wire hooks *g g* are connected at their lower ends with heddles *k k*, through the eyes of which pass threads of the warp of the lower web of cloth in the loom, shown in blue; and the particular threads of the warp required for stitching the seam or seams for joining the two webs of cloth are lifted when the griff-frame rises, to be woven in with the upper web of cloth.

The seams *m m*, figs. 9, 10, thus made for joining the upper and lower webs of cloth together, to form a series of garments or parts of garments in the same web, may be run in any desired direction, according to the form and position of the cams *H*, operating on the needles *d d*, for lifting such stitching-threads as are needed to do the work.

It will be readily perceived that if one single seam, or two parallel seams are to be made, running lengthwise of the web of cloth in a straight line, the cam or cams will be limited in operation to those needles, *d d*, that will make the proper stitching by lifting the same thread or threads of the warp-yarn in concert with the operation of weaving the upper web of cloth, but if the single or double seams are to be made at right angles across the web, then the cam must be made to extend across the loom-frame, and operate on all the horizontal needles simultaneously, to lift all the threads of the warp-yarn at once. But for making diagonal or curved seams, figs. 7, 8, the form of the face of a single cam extending across the frame, or of single travelling-cams, as previously described, will be made in accordance with, the desired angle of divergence from a right angle, or with the curve to be given to the seam or seams *m m*, which are shown running longitudinally and transversely, in straight lines and curves, to form the garments, as shown in figs. 9, 10, wherein are exhibited illustrations of my improved method of weaving and stitching double cloth together at the same time, to form a series of garments with the same web.

For thus stitching continuous single or double seams side by side, and uniting double cloth when woven, to make a series of garments, as illustrated in figs. 9, 10.

I am aware that two webs of cloth have been woven and stitched together at the same time to make quiltings and other double-cloth goods, and that even single garments have been thus made, and I disclaim, therefore, as my invention the plans and methods of weaving and uniting double cloth which have been employed for such purposes; but

I do claim as my invention, and desire to secure by Letters Patent—

1. The combination of the sliding cams *H*, shaft *b*, gear *G'*, and worm-wheel *G*, with the needles *d*, and guide-rods *c c*, for weaving the necessary pattern, substantially as herein shown and described.
2. In combination with the above, the shaft *a*, screw-worm *G*, and pinion *G'*, substantially as and for the purpose herein shown and described.

The above specification of my invention signed by me, this 1st day of May, 1867.

SAMUEL LEATHER.
